United States Patent Office.

J. S. VAN BUREN, OF NORWICH, CONNECTICUT.

Letters Patent No. 89,185, dated April 20, 1869.

IMPROVEMENT IN COAL-STOVES.

The Schedule referred to in these Letters Patent and making part of the same.

To all whom it may concern:

Be it known that I, J. S. VAN BUREN, of Norwich, in the county of New London, and State of Connecticut, have invented a new and improved Heater; and I do hereby declare that the following is a full, clear, and exact description thereof, which will enable others skilled in the art to make and use the same, reference being had to the accompanying drawings, forming part of this specification, in which—

Figure 1 is a side view of my improved heater.

Figure 2 is a horizontal section of the same, taken through the line xx , fig. 1.

Similar letters of reference indicate corresponding parts.

My invention has for its object to furnish an improved heater, which shall be so constructed as to utilize a much larger proportion of the heat, developed by the combustion of the fuel, than is possible with the stoves and heaters constructed in the ordinary manner; and

It consists in the construction and combination of the various parts, as hereinafter more fully described.

A is the base of the heater, in which is formed a close chamber, a^1 , extending around the sides, and rear end of the ash-pit a^2 , as shown in fig. 2.

B is the body of the heater, which should be furnished with a grate and fire-pot, in the ordinary manner.

Upon the top of the body B of the heater, is formed a dome, b' , into which the heated products of combustion rise, and from the top of which they pass through an opening, into the dome C, placed directly above the dome b' .

The dome C may be placed directly upon the top of

the dome b' , or they may be connected to each other by a short pipe, as shown in fig. 1.

The latter construction I prefer, as giving a finer appearance to the heater.

The upper dome C is connected with the chamber a^1 of the base A, by four pipes, two upon each side, the front ones, D, being made larger than the rear ones, E, so as to equalize the draught, and also the distribution of heat.

From the chamber a^1 the products of combustion pass into the egress-pipe or flue F, through which they pass to the chimney.

The pipe or flue F is also connected directly with the upper part of the body B of the heater, to supply a direct draught, when required, by a short pipe, G, which should be provided with a damper.

Having thus described my invention,

What I claim as new, and desire to secure by Letters Patent, is—

1. Constructing the heater with two domes, placed one directly above the other, substantially as herein shown and described, and for the purpose set forth.

2. Forming the rear pipes E smaller than the front pipes D, substantially as herein shown and described, and for the purpose set forth.

3. An improved heater, formed by the combination of the close chamber a^1 of the base A, body B, domes b' and C, larger pipes D, smaller pipes E, and egress-flue F, with each other, said parts being constructed and arranged substantially as herein shown and described, and for the purpose set forth.
